UNITED STATES PATENT OFFICE.

MASKLIN C. BAKER, OF NEW YORK, N. Y.

ENGINE-VALVE.

SPECIFICATION forming part of Letters Patent No. 319,661, dated June 9, 1885.

Application filed May 26, 1884. (No model.)

To all whom it may concern:

Be it known that I, MASKLIN CLARK BAKER, a citizen of the United States of North America, and a resident of the city, county, 5 and State of New York, have invented a new and useful Improvement in Engine-Valves, of which the following is a specification.

The object of this invention is to provide an improved steam-engine slide-valve which, 10 in comparison with other slide-valves with the same throw of the eccentric, will give double the opening into the steam-chest, or with one-half of the eccentric throw will give the same opening that the ordinary slide-valve will give 15 with the full eccentric throw.

My improved valve consists of a cylinder open at both ends, provided with steam-ports, cut away centrally in its lower half, and there provided with an elevated cross-bar, which 20 creates an exhaust-steam passage, and which also serves to make the valve-stem connections to. This valve is inclosed in a longer fixed semi-cylindrical shell, also open at both ends, and having the valve-seat as its bottom, and 25 both valve and shell are set within the steam-chest, so that the valve itself operates as a float or balance valve.

Reference is to be had to the accompanying drawings, forming part of the specification, in 30 which similar letters of reference indicate corresponding parts in all the figures.

Figure 1 is a sectional side elevation of my improved valve in position on line xx , Fig. 2. Fig. 2 is a sectional end elevation of the same 35 on line yy , Fig. 1. Fig. 3 is a sectional end elevation of the same on line zz , Fig. 1.

In the drawings, A represents the valve, cylindrical in shape, and having both ends open, as shown at a . Centrally in its lower half it 40 is cut away, and in the opening thus made is fixed, so as to form an integral part of the valve, an elevated cross-bar, b , whose side buttresses, c , are half-round on their inferior faces, in exact correspondence with the periphery 45 of the valve itself. This cross-bar b being elevated at the center, between its buttresses or sides c , affords a port, d , for the escape of exhaust-steam.

Perforated lugs f , forming parts of the cross- 50 bar b , extend upward, and embracing the valve-stem B are properly secured thereto.

At either side of the cross-bar b steam-ports $g g'$, respectively, are formed for the passage of live steam from the valve into the steam-cylinder ports.

C represents the shell inclosing the valve. It is longer than the said valve, as shown, by about twice the width of a supplementary or end steam-ingress port of the valve-seat, the reason for which will hereinafter appear. This 60 shell C is flanged at the sides, as shown at $h h$, Figs. 1 and 2, and said flanges $h h$ being held between the flanges $m m$ of the steam-chest D and the flanges $o o$ of the steam-cylinder E, and properly bolted in place, hold the said 65 shell C rigidly in position.

The steam-chest D, fixed over the shell C, has ample steam-room, as seen at $p p$, and steam is designed to be admitted thereto through pipe D'.

The valve-seat E' of the shell C has four steam-entrance ports, two of which may be called the "outer" or "supplementary" ports, $g g'$, and two the "inner" or "regular" ports, $s s'$, respectively, which latter are twice as wide 75 as the outer ports, and it has also a central exhaust-port, t .

Beneath the valve-seat E' is an ample steam-chamber, t' , from which at each end a steam-port, v , opens into the steam-cylinder E.

The valve-stem B is suitably held and guided in stuffing-boxes and glands $w w'$, respectively.

When the parts are in the position shown in Fig. 1, it will be seen that no steam can enter nor exhaust from the steam-cylinder. Now, 80 if the valve-stem B, carrying the valve A, be moved, say, to the left, by the eccentric, (not shown,) the left-hand buttress of the cross-bar b gradually uncovers the valve-seat port s , so that the steam-cylinder may exhaust through 85 said port and into exhaust-ports $d t$ and exhaust-pipe t' . (Shown in dotted lines.) As the valve A moves farther to the left, the regular port s for the escape of the exhaust is further opened, and at the same time the valve-port g' opens into the regular port s' and delivers steam therein, opening fully into the port s' by the time the port s is fully uncovered. When the valve-port g' begins to open 95 into the regular port s' , the right-hand end of 100 the valve itself begins to uncover the supplementary port g' of the valve-seat, so that steam

from the steam-chest shall enter the port q' at the same moment and in the same degree that it enters the port s' . As each of these ports is designed to be of the usual dimensions of 5 steam-engine steam-ports, it will be seen that by this device I secure in comparison with other slide-valves twice the amount of steam-inlet openings during a full throw of the eccentric or full stroke of the valve, or the 10 same amount in a half-throw of the eccentric or stroke of the valve, a great advantage to the link-motion of locomotives with their short cut-offs. It will be seen that at the end of this stroke of the valve to the left the port 15 a remains fully open and the supplementary port q covered, and that the regular port s' is half opened, the right-hand half thereof, and the supplementary port q' fully open or uncovered, so that full steam is entering the 20 right-hand end of the steam-cylinder, and the exhaust is fully open at the left-hand end. Now, on the return-stroke of the valve A the ports $s' q'$ become covered, while the exhaust s is still about half open, the steam-ingress is 25 cut off, and the steam works expansively in the cylinder until steam is admitted into the left-hand end of the cylinder by the opening of the valve-port g and the left-hand end of the valve into the ports $s q$, respectively, and 30 when this motion of the valve is completed the exhaust s' is fully open and no steam is entering through the right of the valve.

It will be seen that the valve A , having steam within and beneath it—floats, as it were, 35 in the steam—is a float-valve moving with a minimum of friction.

It will be noticed that the exhaust-port d of the valve is of sufficient area to give immediate and full relief to the exhaust-steam from 40 the exhaust-ports, and that when the exhaust takes place the supplementary port on that end is always covered by the lap of the valve.

This form of valve construction with the 45 supplementary steam passages or ports in the valve-seat is especially adapted to high-speed engines or those requiring constant and large amounts of steam; but for engines of low speed I sometimes dispense with the supplementary ports or passages.

50 The shell inclosing the valve and the engine-cylinder can both be cast in one piece, if desirable.

I am aware that it is not broadly new with me to provide auxiliary steam-inlets, as such 55 ports are shown in Patent No. 144,282, of 1873. In that device, however, the valve is not balanced.

In Patent No. 209,305, of 1875, is shown a cylinder-valve moving within a fixed cylinder; 60 but that device provides only the ordinary

single steam-ports upon either side of the exhaust.

Having thus described my invention, I claim as new and desire to secure by Letters Patent—

1. The combination, with a valve-seat having two steam-ports upon either side of a central exhaust, of a balanced valve consisting of an open cylinder having two ports, as $g g'$, and of such length as to uncover the outer ports of the valve-seat when the valve-ports register with the inner ports thereof, as set forth. 70

2. The valve A , of open cylindrical form, having cross-arch, with exhaust-port, and steam-ports, as $g g'$, combined with a valve-seat having two inner ports, as $s s'$, and two 75 outer supplemental ports, as $q q'$, both ports upon either side being uncovered simultaneously by the movement of the valve, as set forth.

3. The combination, with the valve A , as described, of the shell C , having its bottom 80 formed into regular ports $s s'$ and supplemental ports $q q'$, and having flanges h , which are clamped between the corresponding flanges of the steam chest and cylinder, as set forth.

4. The combination, with the shell C , having 85 its bottom formed into a valve-seat with ports $s s'$ and $q q'$, of the valve A , in the form of an open cylinder, having the arch b , with exhaust-passage d and ports $g g'$, the said valve being shorter than the shell and adapted to uncover the supplemental ports q or q' as the ports g or g' register with the ports s or s' , respectively, as set forth.

5. The combination, with the shell C and the valve-seat having ports $s s'$ and supplemental ports $q q'$, of the valve A , as described, 95 having ports $g g'$ and exhaust-passage d , the several ports being so arranged that the exhaust-passage will be open upon one side while both ports $s' q'$ or $q s$ are closed upon 100 the other, and that both ports $s' q'$ or $s q$ upon either side of the exhaust will be uncovered simultaneously, as set forth.

6. The combination, with a cylindrical valve, 105 as A , open at both ends, and provided with cross-bar b and ports $d g g'$, of a fixed shell, as C , longer than said valve and inclosing the same, open at both ends, and having as its bottom a valve-seat containing two regular or inner and two supplementary or outer ports, 110 substantially as herein shown and described.

In testimony that I claim the foregoing as my invention I have signed my name, in presence of two witnesses, this 21st day of May, 1884.

MASKLIN C. BAKER.
